UNITED STATES PATENT OFFICE.

RICHARD H. MORROW AND JAMES MORROW, OF WAUKEGAN, ILLINOIS.

DESIGN FOR AN ELECTRIC-VACUUM-CLEANER CASING OR SIMILAR ARTICLE.

42,973.

Specification for Design.

Patented Sept. 3, 1912.

Application filed May 2, 1912. Serial No. 694,738. Term of patent 7 years.

To all whom it may concern:

Be it known that we, RICHARD H. MORROW and JAMES MORROW, citizens of the United States, residing at Waukegan, in the county of Lake and State of Illinois, have invented a new, original, and ornamental Design for an Electric - Vacuum - Cleaner Casing or Similar Article, of which the following is a specification, reference being had to the accompanying drawing, forming part thereof, and wherein—

Figure 1 is a side elevation of an electric

vacuum cleaner casing. Fig. 2 is a view in front elevation thereof. Fig. 3 is a perspective view.

We claim:

The ornamental design for an electric vacuum cleaner casing or similar article, as shown.

RICHARD H. MORROW.
JAMES MORROW.
